US0D1097413S

(12) **United States Design Patent** (10) Patent No.: **US D1,097,413 S**
(45) Date of Patent: ** Oct. 7, 2025

(54) **MOP HEAD**

(71) Applicant: **Yijing Lin**, Zhejiang (CN)

(72) Inventor: **Yijing Lin**, Zhejiang (CN)

(**) Term: **15 Years**

(21) Appl. No.: **29/966,635**

(22) Filed: **Oct. 3, 2024**

(51) LOC (15) Cl. **07-05**

(52) U.S. Cl.

USPC **D32/50**

(58) **Field of Classification Search**

USPC D32/41-42, 46, 50-52; D30/158; D4/116, 118

See application file for complete search history.
